UNITED STATES PATENT OFFICE.

JOHN SPUCK, OF ST. LOUIS, MISSOURI.

FIRE-ESCAPE.

SPECIFICATION forming part of Letters Patent No. 729,437, dated May 26, 1903.

Application filed September 9, 1902. Serial No. 122,693. (No model.)

To all whom it may concern:

Be it known that I, JOHN SPUCK, of the city of St. Louis, State of Missouri, have invented certain new and useful Improvements in Fire-Escapes, of which the following is a full, clear, and exact description, reference being had to the accompanying drawings, forming a part hereof.

My invention relates to improvements in fire-escapes, and has for its object to provide an improved extension to be used in connecting the lower platform of any of the stationary fire-escapes now in use with the ground by means of a ladder or a series of steps which is held up from the ground when not in use.

My invention consists in a peculiar arrangement and construction of parts herein-after described and claimed and which will be more fully understood by reference to the accompanying drawings, which form part of the specification, in which—

Figure 1 is a side view of a fire-escape embodying my invention. Fig. 2 is a perspective of the automatic trigger-bar employed by me in releasing the ladder or steps of my fire-escape when it is desired to form connection with the ground. Fig. 3 is a front view of my invention when the steps or ladder is in connection with the ground. Fig. 4 is a top view of the same. Fig. 5 is a view of the latch by which the steps or ladder used in my invention is caught and held in contact with the ground while in use.

The essence of my invention consists in providing an improved self-contained weight and adjacent parts for use in counterbalancing the weight of a ladder or flight of steps used in forming a connection between the lowest platform of a stationary fire-escape and the ground and suspending the same in such manner that the weight and movement of a person desiring to use the same will be sufficient to cause its automatic deflection.

In the form shown in the drawings a pair of compound trusses 1 form the sides of the ladder or flight of steps 2, the member 3 serving as a hand-rail, the member 4 as the lower support of the hand-rail, the member 5 as the upper support of the hand-rail, and the member 6 as the foundation member of the ladder or flight of steps. The member 6 forms throughout the upper portion of its length a

part of the upper member of the lattice-truss, of which the other members are the base member 7 and the connecting member 8, which latter member is approximately horizontal when the ladder or flight of steps is in use. The structure thus formed is pivoted upon the shaft 9 and contains at its inner upper extremity the special counterbalance-weight 10, which is fixed between the inwardly-projecting ends of the lattice-trusses. The base member 7 acts as a brace for the horizontal connecting member 8 and extends from the free end of the latter in a diagonal direction to a point about midway of the length of the step member 6. The outer side of the platform to which the ladder or flight of steps is pivoted is provided with the platform 11 and the frame 12, and the side from which the ladder or flight of steps leads is provided with the frame 13. A chain 14 is fastened at the bottom of the platform 11 by means of the hook 15 and is attached to the inner end of the lattice-truss by means of the hook 16.

When not in use, the trussed structure is held horizontally, as indicated by the dotted lines in Fig. 1. Further upward movement of the ladder or flight of steps is prevented by the chain 14, which is then taut. In order to prevent the ladder or flight of steps from being lowered from without the building and platform to which the fire-escape is attached, I have provided the trigger 17, which is pivoted in the bearing 18, which bearing is attached to the lower member of the framework 12, the trigger 17 being provided with an inwardly-extending arm at its upper extremity, as shown in Fig. 2, and being connected by the hinged rod 19 with the bar 20, which is pivoted in bearings 21 and 22 upon the outer vertical member of the framework 13 in such manner that when the ladder or flight of steps is not in use the upper and horizontal portion of the bar 20 is placed across the ladder or fire-escape, and the trigger 17 by means of its pivoted connection with the rod or bar 20 extends across the top of the truss member 8, thus serving to hold the ladder or flight of steps in horizontal position.

When it is desired to use the fire-escape, the body of the person seeking egress presses

upon the transverse portion of the bar 20, thus releasing the trigger 17, and the weight of the person who then steps upon the upper rung or step causes the structure to deflect 5 and form contact with the ground.

In order that the ladder or flight of steps when deflected may be held in position, the latch 23 is provided, which catches the truss member 8 as it ascends and holds it in position. It will thus be seen that the operation 10 of my fire-escape is practically automatic and requires nothing beyond the movement of the person desiring to use it to put it in position and provide means of escape.

15 In my structure the counterbalancing-weight 10 is self-contained between the inwardly-projecting ends of the parallel horizontal members 8, which form a part of the step structure and are hinged thereto, as before specified. Said weight 10 is preferably in cylindrical form, as shown, and extends continuously in a horizontal direction from one of said horizontal members 8 to the other, so that an equal amount of weight is applied to each of 20 said horizontal members. By such construction I avoid the undue strain of placing all of the counterbalancing-weight upon one side of the steps or ladder, as has heretofore been done. The weight of the counterbalancing- 25 weight is such as to overcome the weight of 30

the arm of the step structure, which is beyond the point of pivotal connection between the platform and the step structure, and there is therefore practically no strain upon the connecting-chain 14 when the step structure is in 35 horizontal position, as indicated by the dotted lines in Fig. 1, so that even if the connecting-chain 14 were to become rusted it would not affect the operation of the step structure. 40

Having thus described my invention, what I claim as new, and desire to have secured to me by the grant of Letters Patent, is—

The improved ladder connection for platform fire-escapes, comprising a platform, a 45 ladder pivotally connected thereto and provided with two parallel connecting members 8 extending beneath said platform, and a special counterbalancing-weight 10 fixed between said horizontal members 8 and extending 50 in a horizontal direction continuously from the free end of one of said members to the free end of the other horizontal member, substantially as specified.

In testimony whereof I affix my signature 55 in presence of two witnesses.

JOHN SPUCK.
